UNITED STATES PATENT OFFICE.

FRITZ MÄYER, OF NUERMBERG, GERMANY, ASSIGNOR TO BERTA STOERZER, OF BROOKLYN, NEW YORK.

CONTINUOUS KILN.

Application filed August 9, 1921. Serial No. 491,049.

(GRANTED UNDER THE PROVISIONS OF THE ACT OF MARCH 3, 1921, 41 STAT. L., 1313.)

To all whom it may concern:

Be it known that I, FRITZ MÄYER, citizen of Germany, residing at Nuremberg, Bavaria, Germany, have invented certain new and useful Improvements in Continuous Kilns (for which I have filed applications in Germany filed September 7, 1915, Patent No. 328,985, and France filed July 20, 1920), of which the following is a specification.

10 My invention relates to improvements in continuous kilns for burning tile, brick and other earthenware articles, and has for its object to provide means for utilizing the heat of the burning chambers of such kilns 15 for heating the drying chambers ordinarily employed in connection therewith.

With this object in view there are formed in the upper wall of the kiln passages connected by suitable openings with the burning chambers of the kiln and in which are located water pipes adapted to be connected to the piping in the drying chambers employed in connection with such kilns, so that a circulation of water is maintained there- 25 through and the necessary heat supplied to these chambers.

In order to prevent the hot gases passing through the passages from a chamber of the kiln which is at a high temperature to a 30 chamber of a lower temperature, the passages are divided by partitions into compartments corresponding in length with the burning chambers of the kiln.

It has heretofore been proposed to embed 35 such water pipes in the upper walls of the kiln, but in such a construction there is utilized only the heat radiated from the brick work and the entire available heat of the hot gases of the burning chambers is not 40 utilized.

In the accompanying drawings illustrating my invention,

Figure 1 is a horizontal section of a kiln taken on the line 1—1 of Figure 3;

45 Figures 2 and 3 are respectively a vertical longitudinal section and a vertical transverse section thereof, taken on the lines 2—2 and 3—3 of Figure 1;

50 Figures 4, 5 and 6 are similar views illustrating a modification of the invention, and

Figures 7, 8 and 9 are similar views illustrating a further modification thereof.

The kiln shown has the usual tunnel, *g*,

connected to a central smoke flue which leads to a discharge stack, (not shown). 55 The tunnel is divided into burning chambers by temporary partitions, which may be of paper which is burned away as the firing progresses. Charging ducts, *i*, extend through the upper wall of the kiln, through 60 which the fuel is introduced into the kiln tunnel, and are provided with the customary closures.

In the upper wall of the kiln are located 65 passages, *d*, extending throughout the length of the kiln and in open communication with the burning chambers thereof. These passages are divided by partitions, *h*, into compartments corresponding in length with the burning chambers. In these passages, *d*, are 70 placed water pipes, *a*, which are so connected to the piping of the drying chambers as to provide for a circulation of water therethrough, the pipes, *a*, in connection with the piping with the drying chambers 75 forming a hot water heating system for these chambers.

In the form shown in Figures 1, 2 and 3, the passages, *d*, are located directly over the kiln tunnel and are in open communication 80 therewith through openings *e*, formed in the roof of the tunnel.

In the form shown in Figures 4, 5 and 6, the passages, *d*, are located directly over the kiln tunnel and the charging ducts, *i*, are 85 utilized to connect these passages to the burning chambers, openings, *e'*, being formed in the side walls of the passages and connecting the ducts, *i*, thereto.

In the form shown in Figures 7, 8 and 9, 90 the passages, *d*, are located centrally of the kiln directly over the smoke flue. These passages are separated by a partition wall, *k*, and each passage is connected to the burning chambers of the kiln by cross passages, 95 *f*, extending from each passage over the kiln tunnel and connected to the charging ducts, *i*, by passages *e''*.

In each of the forms shown there is an open connection between the passages, *d*, and 100 the burning chambers of the kiln and there is an efficient utilization of the heat of the gases generated in the latter in heating the water in the pipes, *a*.

By dividing the passages, *d*, into compartments corresponding in length to length 105

of the burning chambers of the kiln, the passage of gases from a chamber which is at a high temperature to one which is at a lower temperature is provided and the use of slides or dampers for this purpose is rendered unnecessary, with a consequent cheapening of construction.

Having thus described my invention what I claim as new is:

- 10 1. A continuous kiln having a passage located in the upper wall thereof, openings in said wall connecting said passage with the burning chambers of the kiln, partitions in said passage dividing it into compartments corresponding in length to the length of the burning chambers of the kiln and water pipes in said passage adapted to be connected to the piping in a drying chamber.
- 15 2. A continuous kiln having passages in the upper wall thereof, openings in said wall connecting the said passages with the burning chambers of the kiln, partitions in said

passages dividing them into compartments corresponding in length to the length of the burning chambers of the kiln and water pipes in said passages adapted to be connected to the piping in a drying chamber.

25 3. A continuous kiln having a passage formed in the upper wall thereof, charging ducts passing through said wall and into the burning chambers of the kiln, connections between said charging ducts and said passage, partitions in said passage dividing it into compartments corresponding in length to the length of the burning chambers of said kiln and water pipes in said passage adapted to be connected to the piping in a drying chamber.

30 In testimony whereof I affix my signature in presence of two witnesses.

FRITZ MÄYER.
